UNITED STATES PATENT OFFICE.

WILLIAM W. KINSLEY, OF JAMESTOWN, KANSAS.

DISPENSING DEVICE.

Application filed December 6, 1922. Serial No. 605,244.

To all whom it may concern:

Be it known that I, WILLIAM W. KINSLEY, a citizen of the United States, and a resident of Jamestown, in the county of Cloud and 5 State of Kansas, have invented a new and Improved Dispensing Device, of which the following is a specification.

This invention aims to provide a fountain tooth brush characterized by the presence 10 of a holder or handle for a removable brush head, such holder including a combination of parts so designed and arranged that the length and diameter of the preferably generally cylindrical holder are not materially 15 increased of those of the usual tooth brush handles, fountain pens or the like; and a fountain tooth brush so constructed that the holder is a housing which may be readily opened and which when closed may contain 20 a readily renewable dentifrice tube; that the holder is provided with a removable housing cap for the bristles of the brush head and adapted to aid in the performance of a novel sterilizing function relative to 25 the bristle tufts when the brush is not in use, that the extrusion means for the dentifrice in the dentifrice tube is adapted to extrude practically 100% of the dentifrice and yet without twisting any of the portions 30 of the tube or connecting any part of the tube to the extrusion means or wrapping any such part around any part of the extrusion means and indeed solely as the result of rolling and squeezing the tube exactly as such 35 tube is emptied when tube of the familiar kind is held in the hand; and that the entire instrument is comparatively inexpensive as compared with its manifold advantages.

These advantages, and the invention 40 itself, will be more clearly understood from the following description, when taken in connection with the accompanying drawing showing a preferred embodiment.

In said drawing—

45 Fig. 1 is a side elevation of said embodiment, with a bristle-protecting cap surrounding the bristles and with such cap shown in section;

Fig. 2 is a longitudinal section on line 50 2—2 of Fig. 1;

Fig. 3 is a side elevation of the brush head, detached;

Fig. 4 is a side elevation of the doubly-threaded rotatable feed-tube, partially 55 broken away and partially in section;

Fig. 5 is a transverse section on line 5—5 of Fig. 2;

Fig. 6 is a transverse section on line 6—6 of Fig. 2;

Fig. 7 is a transverse section on line 7—7 of Fig. 2, with the generally spherically roller-squeezer in elevation;

Fig. 8 is a side elevation of the fixed innermost tube; and

Fig. 9 is a perspective view of the squeezer-journalling traveler for the rotatable-feed tube, detached.

Fig. 10 is a fragmentary perspective view of the collapsible tube.

Similar reference characters refer to similar parts throughout the several views of the drawing.

Referring now particularly to the details of the drawing, the combined handle and outer shell of the new tooth brush is indicated at 9. This member is externally threaded at 10 and 11, so that an internally threaded cap 12 may be mounted on the outer shell, as indicated in Fig. 1, preferably to tightly seal the bristle-carrying brush head when the brush is not in use, or as indicated in Fig. 2, to expose the bristle tufts 13.

These tufts, preferably slightly more spaced than in the ordinary tooth brush, are 83 carried by a shaped hollow brush head 14 providing a dentifrice feeding canal 15 opening into a suitable plurality of discharge orifices 16, arranged in alternation with the bristle tufts.

The brush head has external threads 17 as indicated in Fig. 3, so that the head may be screwed tight into the internally threaded forward or open end of what may be termed the inner fixed tube 18; since such tube 94 (shown best in Fig. 8) is the innermost permanent tube of the fountain brush, for directly housing the collapsible and replaceable dentifrice-supplying tube or magazine tube 19. The said tube 18 is fixed to the outer shell 9 by the external threads marked 20 in Fig. 8, and by means, if desired, of a set screw as indicated at 21 in Fig. 6. The threaded connection between the brush head 14 and the fixed inner tube 18, however, is necessarily an impermanent one, since brush head 14 must be disconnected each time a new magazine tube 19 is to be substituted. This brush head carries an internally-threaded terminal enlargement of canal 15, by means 11

of which the usual externally threaded tubes are desirably formed of nickel or an alloy thereof, in view of the thinness of the parts and the fine threads; and the adjacency of the traveler 28 and pin 32 to the roller-squeezer, which latter member is preferably 70

5 Figs. 10 and 2, but in Fig. 10 the mouth-stem of the magazine tube is marked 22 in

10 carries the usual closing cap 23 to be discarded before the magazine tube is mounted in the new device as just described.

In order to facilitate the introduction of 10 a new magazine tube, that is, to permit the tube to be first inserted into the interior of fixed inner tube 18, and thereupon to secure the brush head 14 into fixed inner tube and onto the mouth-stem of the magazine tube,

15 at one operation, the magazine tube, in addition to being of a more reduced diameter than usual, to fit in the relatively thin fountain brush of the present invention, carries a transversely projecting pin marked 24 in 20 Figs. 10 and 6, for reception by a longitudinal slot in the fixed tube marked 25 in Figs. 6 and 8. Such arrangement prevents the magazine tube from turning relatively either to the brush head or the fixed inner tube.

25 The only other parts included in the new device are means for squeezing the magazine tube at any time mounted in the brush as just described, that is, for extruding the dentifrice 26 in such magazine tube into 30 the canal 15 and thence through the orifices 16 on to the bristle tufts 13. Such means includes the following parts: Between the outer shell 9 and the fixed inner tube 18 directly surrounding the magazine tube, is a 35 rotatable feed tube 27, internally doubly threaded as shown most clearly in Fig. 4. A plate-like traveler 28 has at opposite sides a series of teeth marked 29 in Fig. 9 for engaging the internal threads of rotatable 40 feed tube 27, so that as the feed tube is rotated in one direction or the other, the traveler moves axially of the feed tube in one direction or the other. The inner fixed tube 18 is longitudinally slotted on opposite sides 45 as at 30 to permit the movement just described. As shown best in Fig. 9, the traveler 28 forms at its forward end a yoke fixedly suspending a pair of shaft journaling fixtures 31 for pivotally mounting on a 50 pin 32, a generally spherical member 33, which may be properly termed the roller-squeezer. Referring now to Figs. 1, 2 and 4, the rotatable feed tube 27, at its rear end, beyond the rear end of the fixed inner 55 tube, carries a reduced generally cylindrical portion 35^a revoluble in a similarly shaped hole in the rear end wall of the casing, as shown clearly in Fig. 2. The portion 35^a protrudes sufficiently to permit the mounting thereon of a knurled operating knob 34, by any suitable means, as by the threaded connection and the set screw indicated in Fig. 2. Such knob is housed by the cap 12 when the cap is arranged as shown in Fig. 2.

The cap, casing and various permanent

tubes are desirably formed of nickel or an alloy thereof, in view of the thinness of the parts and the fine threads; and the adjacency of the traveler 28 and pin 32 to the roller-squeezer, which latter member is preferably 70

of rubber, makes it important that these mounting parts should be of a similar metal. Indeed, base metal parts should be entirely eliminated if the novel hygienic features of the new device are to be preserved. The 75 rubber of the roller-squeezer should be fairly hard to act in a proper manner; and a rubber like that used for the rollers of clothes-wringers is recommended.

Operation.

Normally, the new device is stored or carried, as in the pocket, like a fountain pen, due to its smoothly cylindrical shape and generally small dimensions rendered possible by the combination of parts present, with the cap affixed as in Fig. 1. When it is desired to use the tooth brush, the cap is removed, the knob is turned sufficiently to move the roller-squeezer from the full-line position in Fig. 2 toward the broken line position thereof, the cap is screwed on the rear end of the outer shell of the handle as in Fig. 2, and the brush used in the ordinary way. When the contents of the magazine tube have been completely extruded, the knob is turned in the reverse direction to retract the roller-squeezer all the way, the brush head 14 is unscrewed from the handle proper, thus disengaging the brush head from the outer shell, and the empty magazine tube is dropped out by tilting the device, a new magazine tube is inserted, and the brush head is secured in place again, simultaneously screwing up the latter into the outer shell and on to the new magazine tube.

These additional comments may be made: The journalling fixtures or wings 31 of Fig. 9 are preferably spherical cones, that is, have rounded outermost surfaces forming relatively minute yet smooth continuations of the exterior of the roller-squeezer, and do the final work of completely emptying the magazine tube when the rubber roller is moved to the left from the position shown in Fig. 2 and on to the double walls of the magazine tube. The combination of these inelastic spherical cones and the resiliently compressible roller makes it very easy to turn the knob 34 and at the same time insures that the very last vestige of dentifrice will be extruded from each longitudinal subdivision of the magazine tube as the roller passes over the same. The roller has been described as substantially spherical, but the same may be elliptic or any suitable shape, so long as it is crowned sufficiently to act substantially as just described when the magazine tube is shaped snugly to fit in the inner fixed tube 18. The special magazine

tube preferably intended to be supplied, has its mouth-stem threaded beyond the internal threads of the adjacent end of the fixed inner tube, thereby to insure that after the exteriorly threaded part of the brush head 14 is disengaged from the inner tube, a separation of the head from the casing will positively withdraw with it, the empty magazine tube. In that case, the special operation 10 of tilting the device to drop out the magazine tube after the brush head is disengaged, as above described, is not necessary. Further, the magazine tube is preferably shaped in side elevation as indicated at 15 35 in Fig. 2, contrary to the conventional double taper of such device, to facilitate complete extrusion of the dentifrice as above described, all the way from the extreme tapered end of the tube. It will thus 20 be seen that there has been provided a device well adapted to attain all the ends and objects of the invention hereinabove indicated, but before closing this specification some recommendations should be made, directly 25 related to the kind of dentifrice to be used to obtain all the anticipated benefits of the device. It is of course understood that the dentifrice recommended cannot be claimed herein, and that the claims appended 30 must necessarily be limited to the new structural combinations provided. Nevertheless, one of the principal objects of the present invention is to furnish a truly and attractively 35 hygienic dental instrument to encourage more regular cleaning of and attention to the teeth than heretofore, as is now generally recognized to be one of the fundamental requisites for insuring the general health of mankind. Recalling then that 40 the parts are so designed that when the cap 12 is arranged as in Fig. 1, the brush head 14 is intended to be tightly air-sealed to the joint between the cap and main casing, the dentifrice supplied in the magazine tube 45 should contain enough alcohol (or thymol, or any other suitable volatile ingredient) so that the fumes there from maintain the brush, when it is tightly covered by the cap as in Fig. 1, in a sterile or asceptic condition. Also the content of pumice stone, chalk or similar cakable substance should not be excessive; but this diminution of abrasives is desirable, as prolonging the integrity 50 of the teeth enamel. Further, of course, the chemistry of the dentifrice should be such as to show no reaction to the metal parts of the device which it may possibly contact. As to the alcohol content, it may be explained that alcohol is so much 55 more volatile than water, that sufficient alcohol fumes will always be set up, not only to fill the cap interior, but to be absorbed by the water in the bristles, which should be washed, but left wet after each brushing 60 of the teeth, to maintain said bristles in a

perfectly asceptic condition despite their wetness.

If the bristles may be kept wet, and yet sterile, that condition is of course ideal. It is very likely that with the cap closed an 70 interchange occurs between the two liquids, the water in the bristles and the alcohol, but with the water taking up more alcohol than the alcohol takes up water; as a result of which, each time the cap is removed for 75 using the brush, the bristles will be found to be saturated with a dilute solution of alcohol and water, thus minimizing the usual distaste for using a tooth brush with wet bristles. Any dentifrice to attain the foregoing or analogous advantages may of course be used.

Specific dimensions and other incidental characteristics of the various parts would be here given in detail, in addition to the foregoing, were it not thought that this specification would be verbose beyond warrant, and beyond the requirement of the statute as to the full, clear and exact disclosure required.

It is obvious that the various materials, shapes and dimensions of the elements of the device are immaterial to the present invention, within the scope of protection contemplated by the appended claims; as the structural details of the drawing are only illustrative of a possible way of carrying out the invention.

I claim:

1. In a device of the kind described, a tubular casing adapted to receive a collapsible tube, a rotatable device movable lengthwise of the casing to squeeze the collapsible tube transversely, a threaded tube surrounding said rotatable squeezing device and fixed 105 against endwise movement and rotatable in opposite directions to advance and retract the rotatable device longitudinally of the casing.

2. In a device of the character described, 110 an inner and an outer tubular casing, said inner casing adapted to receive a collapsible tube, means movable longitudinally of the inner casing to squeeze the tube therein, and means disposed between the inner and outer casing and operable from the exterior thereof to move said squeezing means within the inner casing.

3. In a device of the character described, 120 two tubular casings, one of which is adapted to receive a collapsible tube, a squeezing roller movable longitudinally within said tube receiving casing, a rotatable sleeve disposed concentrically about the tube-receiving casing and within said other casing, means carried by the sleeve and extending axially and exteriorly of the casing, whereby to rotate the sleeve, and means carried by the squeezing roller operatively engaging 125 the rotatable sleeve.

4. In a device of the kind described, a tubular casing adapted to receive a collapsible tube, a rotatable device adapted to squeeze said collapsible tube transversely and comprising a substantially spherical rubber roller, auxiliary squeezing instrumentalities disposed at the opposite ends of the axis of said rotatable squeezing device and adapted to act in addition to said roller during its entire extruding travel, and means operable from the exterior of said casing for moving the squeezing device lengthwise of the casing.
5. A device as defined in claim 4 wherein the auxiliary squeezing instrumentalities comprise journaling means for the opposite ends of the axis of the rubber squeezing roller, as and for the purpose set forth. 15
6. A device as defined in claim 4 wherein the auxiliary squeezing instrumentalities comprise journaling means for the opposite ends of the squeezing roller, said journals including spherical cones, as and for the purpose set forth. 20

WILLIAM W. KINSLEY.
